(57) **CLAIM**

The ornamental design for an antenna cover, as shown and described.

DESCRIPTION

FIG. 1 is a top, rear, left perspective view of an antenna cover of our new design;

FIG. 2 is a left side view of our new design shown in FIG. 1;

FIG. 3 is a right side view of our new design shown in FIG. 1;

FIG. 4 is a front side view of our new design shown in FIG. 1;

FIG. 5 is a rear side view of our new design shown in FIG. 1;

FIG. 6 is a top side view of our new design; and,

FIG. 7 is a bottom side view of our new design shown in FIG. 1.

The broken lines showing portions of the article form no part of the claimed design.

The nature of this product is an antenna cover mounted on a work machine.

1 Claim, 7 Drawing Sheets
